UNITED STATES PATENT OFFICE.

GERALD POULTON, OF LONDON, ENGLAND.

STORAGE AND TRANSIT OF INCANDESCENT ELECTRIC LAMPS.

1,110,571.

Specification of Letters Patent. Patented Sept. 15, 1914.

Application filed November 11, 1912. Serial No. 730,666.

To all whom it may concern:

Be it known that I, GERALD POULTON, a subject of the King of Great Britain and Ireland, residing at the city of London, England, have invented Improved Means for the Storage and Transit of Incandescent Electric Lamps, of which the following is a specification.

The object of the present invention is to provide improved means for enveloping incandescent electric lamps so that they can be stored, handled and conveyed in transit with greater facility and safety against filament fracture than ordinarily.

To this end, a box-like wrapper or covering is employed having at one end means adapted to provide a more or less resilient support for the pip end of the bulb and adjustable means adapted to hold the lamp centrally in the wrapper against such resilient support.

One form which the invention may conveniently take is shown in the accompanying drawings of which—

Figure 1 is a perspective view with parts broken away, of the wrapper. Fig. 2 is a plan view of the blank used in producing such wrapper. Fig. 3 is a view showing part of the wrapper separated from the remainder and supporting a lamp.

As here illustrated one end of the wrapper has flaps *a*, *b* which are inclined inwardly to provide a more or less resilient support for the pip end of the bulb which may be received by a perforation *c* in such inclined flap arrangement. Conveniently the flap *a* has a tongue *d* adapted to protrude through an opening *e* in the flap *b*. Since the seating for the said pip end is at a distance from the end of the box, the pip is protected against damage but if desired, as a further safeguard, an additional flap *f* or flat end may be provided on the corresponding end of the wrapper.

g is the retaining tongue for such flap *f*. The lamp indicated at *A*, is held centrally in the wrapper by means of a collar *h* that can be passed over the cap and makes contact with the walls of the wrapper, the lamp being held against its said seating *a*, *b*, *c* by suitable means such as a thread *i* or threads, stretched across the wrapper by way of slits *j*, *k*, or apertures, in the latter and bearing upon say the collar *h* surrounding the cap. Such thread retaining means affords a simple way of accommodating

lamps of different length and furthermore permits of the wrapper being left open-ended at the cap end of the lamp so that the lamp, after being packed, can be readily tested at any time without removal, one or more side walls of the wrapper being, as is known, provided with inspection openings indicated at *m*, *m*. For the purpose of easily securing the thread, tongues *n*, *n* under which it can be passed, are formed in the wrapper. The thread *i* after the lamp has been packed, may if desired, be sealed in place, it may be for example by an adhesive label. When removing the lamp, the collar *h* around the cap is or may be removed with it and serves or may serve as a support for the lamp to prevent it rolling when placed on its side, as will be understood from Fig. 3.

The wrapper may be made of cardboard, a suitable blank, such as shown in Fig. 2, being creased, folded and secured at adjacent edges *o*, say by fasteners *p*, so that it can be stored in a flat or collapsed condition readily to be opened out or extended when required.

What I claim is—

1. Means for enveloping incandescent electric lamps, comprising a wrapper, a flap constituting an extension of one wall having a projecting and perforated tongue producing shoulders at a distance from the hinge thereof greater than half the width of the adjacent walls and a flap constituting an extension of the opposite wall having an opening therein producing a single intermediately disposed shoulder at a similar distance from the adjacent walls, the said flaps being adapted to be turned into the wrapper to cause the tongue to enter the opening until the shoulders engage and lock one flap at an angle to the other thereby providing intersecting surfaces for supporting the lamp at its pip end.

2. Means for enveloping incandescent electric lamps comprising a wrapper open at one end, a flap, constituting an extension of one wall at the other end having a projecting and perforated tongue producing shoulders at a distance from the hinge thereof greater than half the width of the adjacent walls, a flap constituting an extension of the opposite wall having an opening therein producing a single intermediately disposed shoulder at a similar distance from the adjacent walls, the said flaps being adapted to

be turned into the wrapper to cause the tongue to enter the opening until the shoulders engage and lock one flap at an angle to the other thereby providing intersecting surfaces supporting the lamp at its pip end and a third flap constituting an extension of one of the walls adjacent to both flaps aforesaid, adapted to close this end of the wrapper and protect the flaps.

- 10 3. In means for enveloping incandescent electric lamps, the combination with an open ended wrapper having slits in opposite walls at the open end and a support near the other end for a lamp to rest upon and a self adjusting removable collar therein adapted to be passed over the cap of the lamp leaving

the said cap exposed free to enter a test socket of a twin thread adapted to be passed along the slits in the wrapper so as to bear upon the collar at opposite sides of the cap 20 whatever the position of the latter, so as to exert a distributed pressure upon the collar preventing tilt and pressing the lamp upon its support, and means for securing the ends of such thread to the wrapper. 25

Signed at Orient House, London, E. C. this first day of November 1912.

GERALD POULTON.
